CIRCUIT INTERRUPTER

Winthrop M. Leeds, Wilkinsburg, Pa., assignor to
 Westinghouse Electric & Manufacturing Company, East Pittsburgh, Pa., a corporation of Pennsylvania

Application August 12, 1942, Serial No. 454,515

31 Claims. (Cl. 200—150)

This invention relates to circuit interrupters in general, and, more particularly, to arc extinguishing structures therefor.

More specifically, the present invention concerns a method, structure and mechanism for effecting a rapid extinguishment of the arc which is drawn upon the opening of the contacts of a circuit interrupter.

Test results on various types of arc rupturing devices indicate that the interrupting effectiveness measured in volts per inch of break distance increases somewhat with increasing applied voltage. For instance, a given current at 132 kv. may be interrupted, using a conventional two break interrupter, with only twice the break distance that is required to interrupt the same current at 33 kv., although in the former case the voltage is four times as great as in the latter case.

If, however, instead of using the conventional two break contact arrangement, eight breaks are opened simultaneously, it is found that the total break distance in all of the breaks required to interrupt a given current at 132 kv. is about four times the break distance for the same current at 33 kv., with the conventional two break contact arrangement. In other words, the same results are obtained as might be expected if four separate 33 kv. two break circuit breakers were connected in series and operated simultaneously to interrupt the same current at 132 kv.

In terms of total break distance required for arc extinction, the eight break arrangement for 132 kv. is only one-half as effective as the two break arrangement for 132 kv. In terms of arcing time, however, the eight break design will clear the circuit twice as fast as the two break design, i. e., in one-half the time assuming the same lift rod speed.

It would, therefore, seem that the ideal arrangement would be to use as few breaks as possible, only one break preferably, provided that the required break distance can be obtained very rapidly. Instead of using greatly increased mechanical contact opening speeds, I propose to draw a multiplicity of short serially related arcs which will almost immediately thereafter merge into a single arc.

I accomplish the foregoing by utilizing a plurality of movable bridging contacts, said bridging contacts moving in a lateral direction to effect a circuit interrupter opening operation. The movable bridging contacts may be alternately disposed along the axis of the interrupt-

ing structure. Upon the lateral separation of the movable bridging contacts, a multiplicity of serially related arcs are drawn between the moving bridging contacts, but almost immediately, due to the ionization of the arcing space, the plurality of serially related arcs merge into a single arc which extends between the main contacts of the interrupter.

The main contacts of the interrupter may be 10 stationary, or one of the main contacts may be movable and the operating mechanism arranged in such a manner that the lateral separation of the movable bridging contacts is effective simultaneously with the opening movement of the 15 movable main contact away from the stationary main contact.

In my invention there may also be provided 20 a plurality of insulating baffles which may cause the arc to be lengthened in a zigzag path, first as a number of short arcs in series, and then as a single arc. The single arc may be extinguished by the deionizing action of a turbulent gas-blast passing axially through the arc extinguishing structure.

25 The general principle of my invention, that is, establishing very rapidly an arc between two main contact members may be applied to many conventional arc extinguishing structures already well known to the art, and it is also susceptible to a number of modifications which may actually 30 improve the operation of these conventional devices in terms of required break distance to extinguish an arc.

For instance, it is known that in any arc rupturing device employing a chamber type arc interrupting structure from which a bayonet-type contact is withdrawn, the interrupting effectiveness is improved by making the diameter of the bayonet-type contact and the diameter of the 35 chamber opening as small as possible. In the interrupting structure of my invention the effective cross-section of the opening through the structure may be made quite small without reducing the normal current carrying capacity of 40 the contacts, particularly if one or more baffles are extended into notches or recesses in the faces of the intermediate movable bridging contacts.

Additional effectiveness may be obtained in the 50 arc interrupting structure of my invention by utilizing a plurality of baffles which give a cross-blast action to the gases with respect to the arc as the gases follow the zigzag path through the interrupting structure.

Also in the interrupting structure of my inven-

tion the motion of the movable intermediate bridging contacts may be used to force liquid, such as oil, from oil pockets into the arcing region.

My invention is applicable to liquid breakers or to gaseous breakers, such as the air-break type. In applying my invention to a liquid breaker, the movement of the intermediate bridging contacts may be utilized to create piston action to force liquid, such as oil, along the axis of the interrupting structure.

My invention is also susceptible to application in gaseous type interrupters which use a gas evolving material. When my invention is used in such an application the insulating baffles may be made of a gas evolving material which, upon contact with the arc, give forth a large amount of arc extinguishing gas to facilitate the extinction of the arc.

My invention may also be easily applied to arc interrupting structures of the grid type, that is, the arc which is rapidly produced in my invention may be easily laterally transferred into a grid structure employing magnetic means to laterally move the arc and to effect its extinction.

Upon an understanding of my invention it will be readily apparent to one skilled in the art that its uses in conventional interrupting structures are manifold, and that numerous applications of it will readily suggest themselves.

It is one of the objects of my invention to provide an improved method of arc interruption whereby an arc of relatively long dimensions is much more rapidly produced than in conventional structures and the lengthened arc is quickly subjected to the deionizing action of gaseous or liquid particles to effect its extinction.

Another object of my invention is to provide in a liquid breaker a novel structure for producing very rapidly an arc of relatively long dimensions, which arc may be subjected immediately to the deionizing action of liquid particles.

Another object of my invention is to provide a circuit interrupter of the air-break type in which an arc is very rapidly lengthened and made to react upon gas evolving material to result in the production of arc extinguishing gas to be used in effecting the extinction of said arc.

Another object of my invention is to utilize my invention in conjunction with well known interrupting structures so that the arc after it is once quickly produced and lengthened, may be acted upon by the extinguishing action of conventional interrupting structures.

Another object of my invention is to provide an improved arc interrupting structure of either the liquid or gaseous type of chamber form, from which a movable bayonet-type contact is withdrawn, and in such a structure to reduce the effective cross-section of the arc extinguishing passage as much as possible, yet having the current carrying capacity of the interrupter unimpaired.

Another object of my invention is to provide in an interrupting structure a rapidly produced arc of considerable length by the use of a plurality of intermediate movable bridging blocks which, when laterally separated, draw a plurality of serially related arcs which immediately coalesce into a single arc of considerable length because of the ionization of the arcing region.

Another object of my invention is to provide means in an interrupting structure for the production of a plurality of serially related arcs, which arcs extend in a zigzag path, and which

arcs tend to merge into a single arc of considerable length which extends along a zigzag path.

Another object of my invention is the provision of an interrupting structure in which is provided 5 two main contacts bridged by a plurality of laterally movable contact blocks, an arc being rapidly produced between the main contacts by the lateral separation of the intermediate contact blocks, and the motion of the lateral separating contact blocks being utilized to force liquid or gaseous particles into the arcing region between the main contacts of the interrupting structure.

Another object is to provide an improved operating mechanism in a circuit breaker of the foregoing type.

I am well aware that modifications of my invention are innumerable, and by my illustrating these embodiments of my invention I do not intend to limit its scope, or to suggest that there 20 are not many other modifications which would readily suggest themselves to one skilled in the art.

Further objects and advantages will be apparent upon consideration of the following specification, taken in connection with the accompanying drawings, in which:

Figure 1 is a side elevational view, partly in section, of a circuit interrupter embodying my invention and shown in the closed-circuit position;

Fig. 2 is a cross-sectional view taken on the line II—II of Fig. 1, and looking in the direction of the arrows;

Fig. 3 is an elevational end view taken at right angles to the view shown in Fig. 1;

Fig. 4 is a reduced plan view of one of the insulating plates used in the circuit breaker shown in Fig. 1;

Fig. 5 is a cross-sectional view, taken on the line V—V of Fig. 4, and looking in the direction of the arrows;

Fig. 6 is a reduced plan view of two cooperating strips used in the grid structure of the circuit breaker shown in Fig. 1;

Fig. 10 is a cross-sectional view of a modification of my invention taken on the line X—X of Fig. 25;

Figs. 11 through 24 are plan and cross-sectional views of the insulating plates used in the modification of my invention shown in Fig. 10;

Fig. 25 is a cross-sectional view taken on the line XXX—XXX of Fig. 10, but showing the interrupter in the open-circuit position;

Fig. 26 is a side elevational view of a modified type of circuit interrupter embodying my invention; and

Fig. 27 is an enlarged side elevational view, partly in section, of the modified type of circuit interrupter shown in Fig. 26.

Referring to the embodiment of my invention shown in Figs. 1 to 9, inclusive, and referring particularly to Fig. 1, the reference numeral 1 designates one of two vertically disposed insulating support plates. The other of the two vertically disposed support plates is shown in Figs. 2 and 3 and is designated by the reference numeral 2. Referring particularly to Fig. 2, there is shown

an arcing grid chamber disposed between the two vertically disposed support plates 1, 2, and designated generally by the reference numeral 5. The arcing grid chamber 5 comprises a plurality of suitably shaped insulating plates, the configuration of which are clearly shown in Figs. 4 to 9, inclusive, and to be described more fully hereinafter. The insulating plates comprising the arcing grid chamber 5 are pressed together between two insulating end plates 4 and 6 by the tie-rods 7. Two insulating base plates 8, 9 are secured by screws 10 to the insulating end plates 4, 6. The arcing grid chamber 5 is rigidly secured between the vertically disposed support plates 1, 2 by screws 11 which terminate in the insulating base plates 8, 9.

A plurality of intermediate laterally movable contact blocks 12 are alternately disposed within the arcing grid chamber 5 to contact one another in the closed-circuit position of the interrupter, as shown in Fig. 1, to provide a current conducting path through the arcing grid chamber 5. Each of the contact blocks 12 is rectangular in shape with the face 14 thereof rounded to make line contact with the adjacently disposed contact blocks 12. Each of the contact blocks 12 is resiliently mounted upon an operating rod 13 for reciprocating lateral movement within the arcing grid chamber 5.

The resilient connection between the contact block 12 and the operating rod 13 is provided by the utilization of a compression spring 15, as more clearly shown in Fig. 2. A U-shaped metallic member 17 is welded to each operating rod 13 and provides a support for one end of the compression spring 15. The other end of the compression spring 15 abuts against the lower face of the contact block 12. The operating rod 13 extends loosely into a hole 19 (see Fig. 2) bored into the lower surface of the contact block 12. A pin 21 extends snugly transversely through the end of the operating rod 13. The pin 21, however, extends loosely through an aperture 23 drilled laterally through the contact block 12. It will therefore be readily apparent that a certain degree of resilience is provided by the compression spring 15 depending upon the relative diameters of the pin 21 and the aperture 23.

The operating rods 13 extending through the lower insulating base plate 9 are rigidly secured to an insulating operating block 25. The operating rods 13 extending upwardly through the upper insulating base plate 8 also are rigidly secured to an insulating operating block 26.

The insulating operating block 25 is pivotally secured by a pin 27 to two insulating links 28, 29, the lower ends of which are pivotally mounted by a pin 31 to a bifurcated lever 33, as more clearly shown in Fig. 1. The bifurcated lever 33 is rotatable about a fixed pivot pin 35, which extends through both vertically disposed support plates 1, 2.

The bifurcated lever 33 is pivotally operable about the fixed pivot pin 35 by means of two link members 36, 37 (see Fig. 3) which are pivotally mounted by means of a pin 39 to the right-hand end of the bifurcated lever 33 as viewed in Fig. 1. The upper ends of the link members 36, 37, as viewed in Fig. 1, are pivotally mounted by a pin 41 to two lever members 42, 43. The lever members 42, 43 are pivotally movable about a fixed pivot pin 45 which extends through the support plates 1, 2. The right-hand ends of the lever members 42, 43, as viewed in Fig. 1, are pivotally connected by means of a pivot pin 47.

to two link members 48, 49. The upper ends of the link members 48, 49, as viewed in Fig. 1, are pivotally secured by a pivot pin 51 to a second bifurcated lever 53, which itself is pivotally mounted about a fixed pin 55 extending transversely through the support plates 1, 2. The left-hand end of the bifurcated lever 53, as viewed in Fig. 1, is pivotally secured by means of a pivot pin 57 to two insulating link members 58, 59, the lower ends of which are pivotally secured by means of a pivot pin 61 to the upper insulating operating block 26.

A tension spring 63 is extended between the pivot pins 51 and 41. It will therefore be seen that the tension spring 63 tends to maintain the interrupter in the open circuit position because of the biasing action exerted by the tension spring 63 on the bifurcated levers 33, 53.

Referring particularly to Fig. 3, it will be noted that two contact fingers 64, 65 are secured on opposite sides of a conducting block 67 and maintained in compressive relation by means of leaf springs 68, 69. The leaf springs 68, 69, which maintain the fingers 64, 65 in compressive relation, are mounted upon a threaded stud 71 (see Fig. 3) which extends through the conducting block 67 and also through two lever members 73, 75. The left-hand ends of the lever members 73, 75, as viewed in Fig. 1, are pivotally mounted on a fixed pivot pin 77 which extends transversely through the support plates 1, 2.

The pivot pin 41 which pivotally connects the lever members 42, 43, respectively, with the link members 48, 49 also extends loosely through the upper portion of the conducting block 67. It will therefore be readily apparent that by virtue of the fixed pivot pins 45, 77 there will be no lateral movement of the conducting block 67 during its upward and downward movement, as viewed in Fig. 1.

A lift rod 79, composed of insulating material, has at its lower end a conducting bridging member 81 (only a fragmentary part of which is shown in Fig. 1), the left-hand end of which, as viewed in Fig. 1, being adapted to engage the contact fingers 64, 65 to separate them and to abut against the lower portion of the conducting block 67 at the point designated by the reference numeral 83 in Fig. 1.

When it is desired to close the electrical circuit through the interrupter shown in Fig. 1, the insulating lift rod 79 is actuated upwardly by external operating mechanism (not shown). The upward movement of the insulating lift rod 79 also moves upwardly the conducting bridging member 81. The conducting bridging member 81 separates the contact fingers 64, 65 and engages the lower portion of the conducting block 67 at 83 (see Fig. 1) to move the conducting block 67 upwardly to result in a counterclockwise rotation of the lever members 42, 43 about the fixed pivot pin 45. This counterclockwise rotation of the lever members 42, 43 about the fixed pivot pin 45 causes, by virtue of the link members 48, 49 and 36, 37, pivotal motion of the bifurcated levers 33, 53 to result in a closing engagement of the contact blocks 12.

During the closed-circuit position of the interrupter, which is illustrated in Fig. 1, the electrical circuit therethrough comprises the external line terminal 85, the conducting adaptor 87, the conducting strap 89, the left-hand stationary contact 91, the contact blocks 12, the right-hand stationary contact 93, the flexible conductor 95, the conducting block 67, the contact fingers 64,

65, the conducting bridging member 81 to the right-hand grid structure of the interrupter (not shown) which is identical to the left-hand grid structure shown in Fig. 1. Both grid structures may be placed in a suitable tank, not shown.

When it is desired to open the interrupter shown in Fig. 1, or when external overload conditions exist in the electrical circuit connected to the interrupter, suitable external operating mechanism (not shown) is actuated to result in downward motion of the insulating lift rod 79. The downward motion of the insulating lift rod 79 permits the tension spring 63 to draw the two pivot pins 51, 41 partially toward each other and hence to result in opening movement of the bifurcated levers 33, 53. The opening movement of the bifurcated levers 33, 53 effects a separation of the contact blocks 12 to result in the drawing of a multiplicity of serially related arcs between adjacently disposed contact blocks 12.

Since the interrupting structure is immersed in a suitable liquid, in this instance oil, the liquid penetrates the entire arcing grid chamber 5. The drawing of a multiplicity of serially related arcs between the contact blocks 12 results in an ionization of the arcing region extending between the left-hand stationary contact 91 and the right-hand stationary contact 93. A vent 97 (see Fig. 1) is provided in the insulating end plate 4 to permit the projection therethrough of gas and products of decomposition resulting from the action of the serially related arcs upon the oil disposed in the arcing region.

Almost immediately upon the creation of a multiplicity of serially related arcs between the contact blocks 12, the arcing region within the arcing grid chamber 5 will be ionized sufficiently to result in a coalescing of the multiplicity of serially related arcs between the contact blocks 12 into a single arc which extends through the arcing grid chamber 5 from the left-hand stationary contact 91 to the right-hand stationary contact 93.

After the merged arc within the arcing grid chamber 5 has been extinguished, and consequently after the electrical circuit has been interrupted through the breaker, the conducting bridging member 81 will then separate from the fingers 64, 65 to effect an additional isolating break in the circuit interrupter.

Referring more particularly to the arcing grid chamber 5 and to Figs. 4 to 9, inclusive, it will be apparent that the arcing grid chamber 5 comprises a plurality of insulating plates pressed together by the tie-rods 7. It will be noticed that disposed in alternate relation and extending inwardly from the insulating base plates 8, 9 are a plurality of relatively thick U-shaped insulating plates 99, the configuration of which is more clearly shown in Figs. 4 and 5. Suitable apertures 101 are provided in the U-shaped insulating plates 99 for the reception of the tie-rods 7. Referring more particularly to Fig. 2, it will be noticed that the bight 103 of the U-shaped insulating plate 99 extends slightly into a recess 105 grooved in the head of the contact block 12, the purpose for which will appear more fully hereinafter.

Immediately adjacent the U-shaped insulating plate 99, on both sides thereof, are two flow insulating plates 107, the configuration of which is more clearly shown in Figs. 8 and 9. The insulating plates 107 are called flow insulating plates because they permit oil disposed behind

the contact blocks 12 to be spurted by the piston action of the moving contact blocks 12, around the sides 109, 110 (see Fig. 1) of the contact blocks 12 and into the arcing region of the 5 arcing grid chamber 5. The oil is thus permitted to flow along the sides 109, 110 of the contact blocks 12 because of a cut-out portion 111 provided in the flow insulating plate 107, as more clearly shown in Fig. 8.

10 Immediately adjacent the two flow insulating plates 107 are four layers, each layer consisting of two strips 113, the configuration of which is more clearly shown in Figs. 6 and 7. Immediately adjacent the four layers just referred to are 15 two flow insulating plates 107, which flow insulating plates 107 are turned opposite to the flow insulating plates 107 previously referred to. Adjacent the two oppositely turned flow insulating plates 107 is a second U-shaped insulating plate 99, but this time also turned in the opposite direction.

20 The further grouping of the insulating plates is identical to that just described, namely a U-shaped insulating plate 99, two flow insulating plates 107, four layers of strips 113, two flow insulating plates 107 oppositely placed, and a U-shaped insulating plate 99 also oppositely disposed.

25 Referring to Figs. 4 to 9, inclusive, and also to Fig. 1, it will be apparent that the contact blocks 12, the sides of which are rectangular in form, are arranged for reciprocating motion in rectangular passages 113 (see Fig. 2). The sides of the rectangular passages 113 are formed by the insulating plates previously referred to, it being noted that the cut-out portions 111 provided in the flow insulating plates 107 provide a bypass for oil to flow from behind the contact blocks 12 through the cut-out portions 111 provided in the flow insulating plates 107 to the arcing region ahead of the receding contact blocks 12.

30 Consequently upon the opening of the breaker and the resulting lateral separation of the contact blocks 12, spouts of oil are ejected along the sides 109, 110 of each contact block 12 into the arcing region transversely of the merged arc which at this time extends between the stationary contacts 91, 93. The ejecting of oil from behind the contact blocks 12 upon the separation 35 thereof, transversely of the merged arc facilitates the extinction of said merged arc.

30 As was mentioned previously, it is well known that in any arc rupturing device employing a chamber type structure from which a bayonet-type contact is withdrawn, the interrupting effectiveness is improved by making the contact diameter and the chamber opening as small as possible. In the embodiment of my invention being described and illustrated in Figs. 1 to 9, inclusive, the effective cross-section of the passage within the arcing grid chamber 5 extending from the right-hand stationary contact 93 to the left-hand stationary contact 91 adjacent the vent 97, may be made quite small by the utilization of the 45 relatively thick U-shaped insulating plates 99, the bight 103 thereof extending relatively far out into the arcing region between the two stationary contacts 91, 93. Provision is made for this relatively far extension of the bight 103 of the relatively thick insulating U-shaped plates 99, by the use of recesses 105 formed in the faces 14 of the contact blocks 12. Since, in my invention, the actual contact between adjacently disposed contact blocks 12 is formed near the sides thereof 50 and not at the extreme end of the head, the re-

cesses 105 provided in the extreme ends of the contact blocks 12 do not interfere with the current carrying capacity of the interrupter.

When the breaker shown in Fig. 1 is opened and the contact blocks 12 laterally separated to form a multiplicity of serially related arcs, the multiplicity of serially related arcs substantially immediately coalesce into a single merged arc extending between the stationary contacts 91, 93 because of the ionization of the arcing region. 10 The single merged arc is extinguished by the deionizing action of the turbulent gas blast passing axially through the arcing grid chamber 5 from the right-hand stationary contact 93 to the vent 97 adjacent the left-hand stationary contact 91. 15 The spouts of oil resulting from the piston action of the contact blocks 12 transversely of the single merged arc, and the necessity for the single merged arc to extend in a zigzag path because of the extensions of the bights 103 of the relatively 20 thick U-shaped insulating plates 99 into the arcing space, all combine to produce an extremely rapid extinction of the merged arc. I have interrupted 1750 amperes at 22,000 volts with only 25 1 cycle of arcing using an interrupter of the type shown in Fig. 1.

The method of producing extremely rapidly a single arc of relatively long dimensions by the production of a multiplicity of serially related arcs, which substantially immediately 30 coalesce into a single merged arc of considerable length in an extremely short time, and thereafter subjecting said single merged arc to the deionizing action of a transverse blast of gaseous and liquid particles in an arcing region of narrow dimensions results in extremely effective interruption of the electrical circuit passing through the interrupting structure. The break distance required to extinguish such an arc is considerably decreased over the break distance required in conventional type circuit interrupters.

I am well aware that one of the features of my invention, namely the establishing of a long arc very rapidly by first producing a multiplicity 45 of short serially related arcs, and then merging said short arcs substantially immediately after their formation into a single merged arc, may be applied to many conventional type circuit interrupters.

The modification of my invention now to be described is illustrated in Figs. 10 to 25, inclusive, and concerns my invention as applied to a liquid type interrupter, using an interrupting structure, similar to that described in United 55 States Patent No. 2,138,382 which issued November 29, 1938, to Winthrop M. Leeds and Ennio Ortensi and which was assigned to the assignee of the present application.

Referring particularly to Fig. 10, there is 60 shown an arcing grid chamber generally indicated by the reference numeral 115 placed between vertically disposed insulating support plates 1, 2. Disposed within the arcing grid chamber 115 are a plurality of contact blocks 12 arranged for lateral separating motion by mechanism which may be similar to that previously described in connection with Fig. 1.

Disposed laterally to one side of the line of motion of the movable contact blocks 12 is a grid 70 structure, which serves to attract the single merged relatively long arc extending between the stationary contacts 91, 93 (see Fig. 25) to the left, as viewed in Fig. 10, and thereafter to extinguish the same. The action of the inter- 75

rupting structure shown in Fig. 10 is similar to that previously described in connection with Fig. 1, but after the merged arc has been formed between the stationary contacts 91, 93, it is moved laterally to the left, as viewed in Fig. 10, by the biasing action exerted by a plurality of inserts 117 composed of magnetic material.

Considering Fig. 25 (which shows the breaker in the open-circuit position) with Fig. 10, it will be apparent that the arcing grid chamber 115 comprises a plurality of insulating plates suitably formed, and more clearly shown in Figs. 11 to 24, inclusive.

It will be observed that alternately disposed within the arcing grid chamber 115 and extending inwardly from the base plates 119, 121 thereof, are a plurality of relatively thick insulating plates 123, the configuration of which is more clearly seen in Figs. 11 and 12. Referring to Figs. 11 and 12, it will be noticed that the insulating plate 123 has formed therein a plurality of apertures 101 for the reception of tie-rods 7. The insulating plate 123 is also provided with a plurality, in this instance three, oil pockets 125, which are joined together and lead into a flared vent opening 127.

Immediately adjacent each relatively thick insulating plate 123, on each side thereof, are two flow insulating plates 129, the configuration of which is more clearly shown in Figs. 13 and 14. It will be noticed that the flow insulating plate 129 has cut-out portions 111 similar to the cut-out portions 111 of the flow insulating plate 107 used in the interrupter previously described in Fig. 1 and shown in Figs. 8 and 9. The purpose of the cut-out portion 111 in the insulating plate 129 is the same as that previously described, namely, the provision of a plurality of spouts of oil from behind the contact blocks 12 laterally along the sides 109, 110 thereof (see Fig. 25) and into the arcing region between the stationary contacts 91, 93.

It will also be observed that the flow insulating plates 129 also contain a plurality, in this instance three, oil pockets 131, the purpose for which will appear hereinafter. Immediately adjacent each set of two flow insulating plates 129 is a set of three insulating plates, the center plate of which is herein called an insert insulating plate 133 and the two outer plates of which are herein called guard insulating plates 135. The guard insulating plates 135 are so-called because they protect the magnetic insert 117 embedded in the insert insulating plate 133 from the direct effect of the arc, which is attracted by the distortion of the magnetic field thereabout into the narrow arcing slot 137.

Immediately adjacent the set comprising one insert insulating plate 133 interposed between two guard insulating plates 135, are two flow insulating plates 129 turned about 180°, as indicated by Figs. 21 and 22. Adjacent the two last-mentioned flow insulating plates 129 is a second relatively thick insulating plate 123 disposed 180° from the position of the preceding relatively thick insulating plate 123, as indicated by Figs. 23 and 24. The successive groupings of the plates are identical to the groupings just described, and consequently a further description thereof seems unnecessary.

Considering particularly Figs. 11 to 24, inclusive, it will be noticed that when the insulating plates are compressed together by the tie-rods 7, the plates form a narrow arcing slot 137 as defined by the insert plate 133 and the two guard

insulating plates 135. It will be noted that the narrow arcing slot 137 is only vented by the vent openings 127 provided in the relatively thick insulating plates 123 (see Figs. 11 and 12). It will be furthermore observed that the provision of the oil pockets 125 in the relatively thick insulating plates 123, and the oil pockets 131 in the flow insulating plates 129 create a readily available supply of liquid, such as oil, adjacent the arc as it is moved into the narrow arcing slot 137 along the wall thereof.

The arc is not permitted to enter the narrow arcing slot 137 until the instantaneous current thereof is relatively low. Before this time the arc is compelled to remain in the enlarged arcing slot 139 of the two guard insulating plates 135 and the insert insulating plate 133.

As was clearly brought out in the aforesaid patent, it is not advisable to attempt the interruption of an arc during the peak values of the instantaneous current thereof. The time most suitable for arc interruption is a time when the instantaneous value of the arcing current is low, that is approaching a current zero. During relatively high instantaneous values of arcing current, the cross-section of the arcing stream is too large to permit it to be forced into the narrow arcing slot 137, and it is consequently positioned adjacent the entrance thereto in the enlarged arcing slot portion 139. Because of the presence of the magnetic inserts 117 in the insert insulating plates 133, the magnetic field surrounding the arc stream is distorted and the arc stream is constantly biased into the narrow arcing slot 137 by a force which varies as a function of the instantaneous value of the arcing current. When the instantaneous value of the arcing current reaches a relatively low magnitude, the cross-sectional area of the arc stream is sufficiently small so that the biasing action exerted by the magnetic inserts 117 is sufficient to move the arc laterally into the narrow arcing slot 137 to effect its extinction.

While the arc is positioned in the narrow arcing slot 137, it reacts upon the oil disposed in the oil pockets 131 in the flow insulating plates 129 and the pockets 125 disposed in the relatively thick insulating plates 123 to result in a production of a quantity of gaseous and liquid particles, which pass transversely through the arc stream and out of the narrow arcing slot 137 through the vent openings 127 provided in the insulating plates 123.

The deionizing action of the liquid and gaseous particles passing transversely through the arc stream while it is positioned in the narrow arcing slot 137, and the constriction afforded by the walls of the narrow arcing slot 137, as formed by the insert insulating plate 133 and the two guard insulating plates 135 in each grouping, affords a very effective extinguishing action upon the arc to result in the extinction thereof. It will be noticed that the arc itself is never permitted to pass out of the narrow arcing slot 137 because the vent openings 127 are only provided in the relatively thick insulating plates 123. It will also be apparent that the deionizing activity of the arcing grid chamber 115 is increased by the spurting of oil into the arcing region by the piston action created by the movement of contact blocks 12.

It will be observed that there is no vent opening in the arcing grid chamber 115 corresponding to the vent opening 97 provided in the structure illustrated in Fig. 1. In the present modi-

fication the effective cross-sectional path between the stationary contacts 91, 93 (see Fig. 25) may be made quite small to increase the interrupting effectiveness of the breaker by the use of the relatively thick insulating plates 123 extending a considerable distance into the arcing path between the stationary contacts 91, 93. Again, notches or recesses 105 may be necessary in the faces of the contact blocks 12 to accommodate the extension of the relatively thick insulating plates 123.

Another modification of my invention is shown in Figs. 26 and 27. In this modification of my invention, instead of having two stationary contacts (such as 91, 93 in Figs. 1 and 25) I employ a stationary contact 141 and a movable contact 143. When the breaker is in the closed circuit position (not shown) the movable contact 143 engages the lower contact block 12, the electrical circuit passing through the interrupter then comprising the movable contact 143, the plurality of bridging contact blocks 12, the stationary contact 141 and an external flexible line conductor 145.

When the breaker is opened, there is a simultaneous downward movement of the movable contact 143 with the lateral separating movement of the contact blocks 12. Any suitable mechanism may be employed to effect this simultaneous movement. For instance, that which is used in the present modification comprises an insulating off standing member 147 which actuates two bell crank levers 149 which are pivotally connected to the insulating operating links 151. The insulating operating links 151 are pivotally connected to the insulating operating blocks 153, 155, in which are embedded the operating rods 13 of the contact blocks 12. The bell crank levers 149 are biased to the open-circuit position by tension springs 157.

It will consequently be apparent that when it is desired to close the breaker, the movable contact 143 is actuated upwardly, and the insulating member 147 attached thereto actuates the bell crank levers 149 against the biasing action exerted by the tension springs 157, to effect a simultaneous movement of the movable contact 143 and of the contact blocks 12.

In the closed-circuit position of the interrupter, indicated by the dotted lines in Fig. 27, it will be noticed that instead of the line contact between the contact blocks 12, as was the case in the previous two embodiments of my invention, there is an abutting engagement between the contact blocks 12, and also between the contact blocks 12 and the stationary and movable contacts 141, 143. The current carrying capacity of the breaker is hence improved by utilizing an abutting engagement of the contact blocks 12 with the stationary and movable contacts 141, 143.

The present modification of my invention concerns an interrupter of the air-break type in which is provided gas-evolving material, in this instance, such as the inwardly extending baffles 159 composed of a suitable gas-evolving material, such as boric acid, horn fiber or other resinous material. It will be noticed that in this modification of my invention the baffles 159 extend considerably inwardly so that the single merged arc between the stationary contact 141 and the movable contact 143 will be brought into intimate engagement with the inner ends 161 of the baffles 159. By such an intimate engagement between the arc and the inner ends 161 of the

gas-evolving baffles 159, there is produced a voluminous amount of arc extinguishing gas, which passes axially downward through the breaker to the vent opening 163 at the lower end of the arcing chamber. It will be noticed however, that before the arc extinguishing gas produced by the action of the arc upon the baffles 159 can pass out of the interrupting structure through the vent opening 163, it must necessarily traverse a zigzag path which is substantially perpendicular to the direction of the arc stream when the latter extends between the stationary contact 141 and the movable contact 143. There is thus consequently produced a very effective extinguishing action of the gas evolved.

Again, in this modification of my invention, the effective cross-sectional area of the arcing passage extending between the stationary contact 141 and the movable contact 143 through the grid structure may be dimensioned to improve the interrupting capacity of the breaker by the inward extension of the baffles 159, but because of the abutting engagement of the contact blocks 12 and the provision of recesses 105, the current carrying capacity of the interrupter is not impaired.

When the breaker is in the open circuit position, there is provided an isolating gap in the electrical circuit passing through the breaker because of the downward movement of the movable contact 143. Upon the downward movement of the movable contact 143, the tension springs 157 effect a lateral separation of the contact blocks 12 to draw a plurality of serially related arcs between the contact blocks 12, and the contact blocks 12 to the stationary and movable contact 141, 143. Immediately thereafter, however, the plurality of serially related arcs coalesce into a single merged arc extending in a somewhat zigzag manner from the stationary contact 141 to the movable contact 143. The production of arc extinguishing gas, as previously described, and the passage thereof transversely through the arc stream, and the diminishment of the effective cross-sectional path through the grid structure from the stationary contact 141 to the movable contact 143, all contribute to result in an effective extinguishment of the merged arc.

My invention may be incorporated in other air-type breakers, or breakers of the type utilizing a blast of compressed gas with the provision of suitable vents provided along the arc passage. The gas blast may be transverse or longitudinal of the arc stream and may be supplied from pumps or other means to assist in the extinction of the arc established by separating contacts of the breaker.

When my invention is utilized in a liquid type breaker, liquid pumps may be utilized and suitable vents provided for the flow of liquid transversely or longitudinally of the arc stream to effect its extinction. Many other modifications and applications of my invention will readily suggest themselves to one skilled in the art.

It will be apparent from the foregoing that I have provided an interrupter which very rapidly produces a single merged arc of considerable length by an initial formation of a plurality of serially related arcs and the substantially immediately merging of said serially related arcs by the ionization of the arcing region through the breaker. This method of producing a long arc of considerable length very rapidly may be used in conjunction with conventional interrupting structures to assist in the extinction of the arc,

or it may be used in air-type breakers of the gas evolving type.

Although I have shown and described specific circuit interrupting structures, it is to be understood that the same were merely for purposes of illustration and that changes and modifications may be made by those skilled in the art without departing from the spirit and scope of the appended claims.

10 I claim as my invention:

1. The method of interrupting an electrical circuit comprising initially forming a plurality of relatively short serially related arcs, merging said arcs into a single arc of considerable length, and then extinguishing said single merged arc of considerable length.

2. The method of interrupting an electrical circuit comprising first producing a plurality of closely spaced breaks in said circuit to form a plurality of relatively short serially related arcs, causing the coalescence of said relatively short serially related arcs into a single arc of considerable length, and extinguishing said single arc of considerable length by deionizing activity.

25 3. In a circuit interrupter, relatively movable contact structure movable to first form a plurality of relatively short serially related arcs, means to merge said plurality of relatively short serially related arcs into a single arc of considerable length, and means for extinguishing said merged arc.

35 4. In a circuit interrupter, a plurality of alternately disposed cooperating contact blocks, said contact blocks being separable to form a plurality of relatively short serially related arcs, means for coalescing said plurality of relatively short serially related arcs into a single arc of relatively long length, and means for extinguishing said single arc.

40 5. In a circuit interrupter, a substantially closed arcing chamber, one or more first contact blocks disposed within said arcing chamber and arranged for simultaneous lateral motion, a plurality of second contact blocks disposed within 45 said chamber and arranged for simultaneous lateral motion, said first and said second contact blocks being alternately disposed with respect to each other and separable simultaneously to form a plurality of relatively short serially related arcs within said chamber, means for merging said plurality of relatively short serially related arcs into a single arc of considerable length, and means for extinguishing said merged arc.

55 6. In a circuit interrupter, a substantially closed arcing chamber, one or more first contact blocks disposed within said arcing chamber and arranged for simultaneous lateral motion, a plurality of second contact blocks disposed within said chamber and arranged for simultaneous lateral motion, said first and said second contact blocks being alternately disposed with respect to each other, and a plurality of insulating baffle members disposed within said arcing chamber.

60 7. In a circuit interrupter, a substantially closed arcing chamber, one or more first contact blocks disposed within said arcing chamber and arranged for simultaneous lateral motion, a plurality of second contact blocks disposed within said chamber and arranged for simultaneous lateral motion, said first and said second contact blocks being alternately disposed with respect to each other, said first and said second contact blocks being arranged for simultaneous lateral separating motion to form a plurality of relatively short serially related arcs, means for merg-

ing said plurality of relatively short serially related arcs into a single arc of considerable length, a plurality of insulating baffles alternately disposed within said chamber and extending from the lateral inner walls of said chamber inwardly to a point adjacent the axis of said chamber, said first and said second contact blocks having recesses to accommodate the inner ends of said baffles.

8. In a circuit interrupter, a substantially closed arcing chamber, stationary contact means disposed at opposite ends of said arcing chamber, one or more first contact blocks disposed within said chamber and arranged for simultaneous lateral motion, a plurality of second contact blocks alternately disposed with respect to said one or more first contact blocks and also arranged for simultaneous lateral motion, said first and said second contact blocks abutting each other in alternate relation along the axis of said chamber extending between said stationary contact means in the closed-circuit position of said interrupter, said first and said second contact blocks being simultaneously separable during the opening of said interrupter to form a plurality of relatively short serially related arcs, said plurality of relatively short serially related arcs merging into a single arc extending between said stationary contact means.

9. In a circuit interrupter, a substantially closed elongated arcing chamber, a stationary contact disposed at one end of said chamber, a second stationary contact disposed at the other end of said chamber, a vent disposed adjacent one of said stationary contacts, one or more contact blocks disposed within said chamber and arranged for simultaneous lateral motion, a plurality of second contact blocks disposed within said chamber and arranged for simultaneous lateral motion, said first and said second contact blocks being alternately disposed with respect to each other and simultaneously movable toward and away from each other, a plurality of insulating baffles extending from the inner lateral walls of said chamber to a point adjacent the axis of said elongated chamber, each contact block movable between two insulating baffles, said contact blocks being cooperable to form a plurality of relatively short serially related arcs, said plurality of relatively short serially related arcs merging into a single arc extending between said stationary contacts, and means for extinguishing said merged arc by a fluid blast through the axis of said chamber and out of said vent.

10. In a liquid break circuit interrupter, a substantially closed arcing chamber, one or more first contact blocks arranged for lateral motion, a plurality of second contact blocks also arranged for lateral motion, said first and said second contact blocks engaging in abutting relation in the closed-circuit position of said interrupter, a piston chamber associated with one or more of said contact blocks so that upon the lateral separating motion of one or more of said contact blocks liquid within said piston chamber is spurted around the sides of the contact block associated with said piston chamber into the arcing region.

11. In a liquid break circuit interrupter, an arcing chamber, a plurality of alternately disposed contact blocks within said chamber, means for separating said plurality of alternately disposed contact blocks to form a plurality of relatively short serially related arcs, and means utilizing the separating motion of said contact

blocks for spouting liquid into the arcing region.

12. In a liquid break circuit interrupter, a substantially closed elongated arcing chamber disposed in an arc extinguishing liquid, a stationary contact positioned at one end of said arcing chamber, a second stationary contact disposed at the other end of said arcing chamber, a vent adjacent one of said stationary contacts, a plurality of operating rods extending through a lateral wall of said chamber and arranged for simultaneous reciprocating lateral motion, each operating rod carrying at its inner end a rectangular contact block with a recessed head, a plurality of second operating rods extending through the opposite lateral wall of said chamber and also arranged for simultaneous reciprocating motion, each of said second operating rods carrying at its inner end a rectangular contact block with a recessed head, said contact blocks arranged to engage in abutting relationship in the closed-circuit position of said interrupter with each other and also with said two stationary contacts to provide a current carrying path through said interrupter, insulating baffle structure disposed within said chamber and interposed between adjacent contact blocks, part of said baffle structure being accommodated by said recesses in said contact heads, said baffle structure also providing a piston chamber associated with each rectangular contact block so that upon the lateral separating motion thereof liquid disposed behind said contact block will be spurted in front of said contact block along the sides thereof into the arcing region, said contact blocks being separable to form a plurality of relatively short serially related arcs which subsequently merge into a single arc extending between said two stationary contacts, a blast of gas and liquid particles longitudinally of said arcing chamber and through said vent assisting in the extinguishing of said single merged arc.

13. In a circuit interrupter, means for initially forming a plurality of serially related arcs, means for merging said plurality of serially related arcs into a single arc of considerable length, and means for effecting a lateral transfer of at least a part of said single merged arc to effect its extinguishment.

14. In a circuit interrupter, an arcing chamber, an adjacently disposed interrupting structure, means for first forming a plurality of relatively short serially related arcs within said arcing chamber, means for merging said plurality of serially related arcs into a single arc of considerable length within said arcing chamber, means for effecting a lateral transfer of at least a part of said single merged arc into said interrupting structure to effect therein the extinguishment of said single merged arc.

15. In a circuit interrupter of the liquid break type, an arcing chamber, relatively movable contact structure disposed within said arcing chamber, said contact structure being movable to first form a plurality of serially related arcs of relatively short length, means for merging said plurality of serially related arcs into a single arc of extensive length, insulating baffle structure forming an adjacently disposed elongated arcing slot, and means for effecting a lateral transfer of at least a part of said merged arc into said elongated arcing slot to effect therein the extinction of said merged arc.

16. In a circuit interrupter, a substantially closed arcing chamber, a stationary contact at one end of said arcing chamber, an opening at

the opposite end of said arcing chamber, a movable contact movable through said opening in the closed-circuit position of said interrupter, and relatively movable contact structure disposed within said chamber and cooperable with said stationary contact and with said movable contact to first form a plurality of serially related arcs during the opening operation of said interrupter, said plurality of serially related arcs merging into a single arc of considerable length extending between said stationary contact and said movable contact.

17. In a circuit interrupter, an arcing chamber, relatively movable contact structure movable to initially cause the formation of a number of short serially related arcs, means for merging said arcs into a single arc of considerable length, and insulation means disposed adjacent the region of formation of said arcs and said single merged arc, said insulation means being at least in part gas-evolving in the presence of an arc.

18. In a circuit breaker of the gas-evolving type, a substantially closed arcing chamber, a stationary contact at one end of said arcing chamber, an opening in the opposite end of the arcing chamber, a movable contact movable through the opening in the opposite end of said arcing chamber, laterally separable alternately disposed contact means to bridge said stationary and said movable contact in the closed-circuit position of said interrupter, baffle structure disposed in said arcing chamber to decrease the effective cross-section of the arc extinguishing passage between said stationary contact and said movable contact, said baffle structure being composed in part of gas-evolving insulating material, said contact means being separable simultaneously with the opening movement of said movable contact to first form a plurality of relatively short serially related arcs which substantially immediately merge into a single arc extending between said stationary contact and said movable contact, said single merged arc being extinguished with the help of the gas evolved from said baffle structure.

19. In a circuit interrupter, a stationary contact, a movable contact, a plurality of alternately disposed laterally separable contact blocks which conductively bridge said stationary contact and said movable contact in the closed-circuit position of said interrupter, said contact blocks being simultaneously movable to initially form a plurality of serially related arcs which substantially immediately merge to form a single arc extending between said stationary and said movable contacts, the lateral separating motion of said contact blocks taking place at the same time the movable contact is being moved to the open circuit position.

20. In a circuit interrupter, a substantially closed chamber, a stationary contact disposed at one end of said chamber, an opening at the other end of said chamber, a movable contact movable through said opening, an arc passage extending between the stationary and movable contacts, and insulating baffle means disposed within said chamber to decrease the effective cross-section of the arc passage extending between said stationary and said movable contacts.

21. In a circuit interrupter, a first contact structure, a second contact structure, both said contact structures arranged for reciprocal motion toward and away from each other to open and close the circuit through said interrupter, a first pivoted lever, a second pivoted lever, both

5 levers being pivoted intermediate their ends, said first contact structure being connected to one end of said first pivoted lever, said second contact structure being connected to one end of said second pivoted lever, and biasing means for urging the free ends of both said pivoted levers toward each other to bias said interrupter to the open-circuit position.

22. In a circuit interrupter, a first contact structure, a second contact structure, said two contact structures arranged for reciprocal motion toward and away from each other to open and close the circuit through said interrupter, a first pivoted lever, a second pivoted lever, both levers being pivoted intermediate their ends, said first contact structure being connected to one end of said first pivoted lever, said second contact structure being connected to one end of said second pivoted lever, spring means for biasing 10 the free ends of said first and second pivoted levers toward each other, a contact member, said contact member being movable to extend said spring means to effect a rotation of both said pivoted levers and a consequent closing motion of said first and second contact structures.

23. In a circuit interrupter, a first contact structure, a second cooperable contact structure, both said contact structures being arranged for reciprocal motion toward and away from each other to open and close the circuit through said interrupter, a first pivoted lever, a second pivoted lever, said first contact structure being connected to one end of said first pivoted lever, said second contact structure being connected to one end of said second pivoted lever, a third pivoted lever, a tension spring connecting the free end of said first pivoted lever to one end of said third pivoted lever, a link member connecting the free end of said second pivoted lever to the same end 20 of said third pivoted lever that one end of said tension spring is fastened to, a contact block pivotally connected to the free end of said third pivoted lever, a contact member, a fourth lever pivoted at one end, the free end of said fourth lever being connected to said contact block to produce linear motion thereof, said contact member operable to engage said contact block to effect an extension of said tension spring to produce rotation of said first and said second pivoted levers to close the interrupter.

24. In a circuit interrupter, a stationary contact, a movable contact, a first laterally movable contact structure, a second laterally movable contact structure, both said contact structures arranged for reciprocal lateral motion toward and away from each other to effect opening and closing of the circuit through said interrupter, a first pivoted lever, a second pivoted lever, said first contact structure being connected to one end of said first pivoted lever, said second contact structure being pivoted to one end of said second pivoted lever, an offstanding member secured to said movable contact to engage the free ends of said first and second pivoted levers to effect a closing motion of said first and second contact structures simultaneously with a closing motion of said movable contact.

25. The method of interrupting an electrical circuit comprising first establishing and lengthening a plurality of relatively short serially related arcs, merging the arcs into a single arc of shorter length than the combined length of the separate arcs, and subjecting at least a portion of the merged arc to arc extinguishing action to effect its extinction.

26. In a circuit interrupter, one or more first movable blunt nosed contact blocks arranged for lateral motion, a plurality of second movable blunt nosed contact blocks also arranged for lateral motion, said first and said second contact blocks being alternately disposed with respect to each other and separable to form a plurality of relatively short serially related arcs.

27. In a circuit interrupter, one or more first contact blocks arranged for lateral motion, a plurality of second contact blocks also arranged for lateral motion, said first and said second contact blocks being alternately disposed with respect to each other and separable to form a plurality of relatively short serially related arcs, the plurality of relatively short serially related arcs merging into a single arc of substantial length following continued separation of the first and second contact blocks.

28. In a circuit interrupter, a first movable contact means, a second movable contact means, the first and second movable contact means being engageable in the closed circuit position of the interrupter, both the first and second contact means being movable to result in separation between the first and second contact means to produce thereby a plurality of relatively short serially related arcs, and means utilizing the motion of the first and second contact means to force arc extinguishing fluid toward the arcs.

29. In a circuit interrupter, a first contact means, a second contact means, the first and second contact means being engageable in the closed circuit position of the interrupter, both the first and second contact means being movable to result in separation between the first and second contact means to produce thereby a plurality of relatively short serially related arcs, the plurality of relatively short serially related arcs merging into a single arc of considerable length upon continued opening movement of the first and second contact means.

10 30. The method of interrupting an electrical circuit comprising first establishing a plurality of relatively short serially related arcs, merging the arcs into a single arc by raising their arc voltages, and subjecting at least a portion of the merged arc to arc extinguishing action to effect its extinction.

15 31. The method of interrupting an electrical circuit comprising first establishing a plurality of relatively short serially related arcs, raising the arc voltage of each of the short arcs so as to cause them to merge into a single relatively long arc of lower total arc voltage, and then subjecting at least a portion of the merged arc to arc extinguishing action to effect its extinction.

WINTHROP M. LEEDS.
